(57) **CLAIM**

The ornamental design for combined wireless earphones and case, as shown and described.

DESCRIPTION

FIG. 1 is a perspective view of the combined wireless earphones and case showing my new design;

FIG. 2 is a front view of a left earphone of the combined wireless earphones and case, shown separately;

FIG. 3 is a rear view of a left earphone of the combined wireless earphones and case, shown separately;

FIG. 4 is a left side view thereof;

FIG. 5 is a right side view of a left earphone of the combined wireless earphones and case, shown separately;

FIG. 6 is a top plan view of a left earphone thereof;

FIG. 7 is a bottom plan view thereof;

FIG. 8 is a perspective view thereof;

FIG. 9 is a front view of a right earphone of the combined wireless earphones and case, shown separately;

FIG. 10 is a rear view of a right earphone of the combined wireless earphones and case, shown separately;

FIG. 11 is a right side view thereof;

FIG. 12 is a right side view of a right earphone of the combined wireless earphones and case, shown separately;

FIG. 13 is a top plan view of a right earphone thereof;

FIG. 14 is a bottom plan view thereof;

FIG. 15 is a perspective view thereof;

FIG. 16 is a front view of the case of the combined wireless earphones and case, shown separately;

FIG. 17 is a rear view thereof;

FIG. 18 is a left side view thereof;

FIG. 19 is a right side view thereof;

FIG. 20 is a top plan view thereof;

FIG. 21 is a bottom plan view thereof;

(Continued)

FIG. 22 is a perspective view thereof;
 FIG. 23 is an enlarged view of portion of FIG. 8;
 FIG. 24 is an enlarged view of portion of FIG. 2; and,
 FIG. 25 is an enlarged view of portion of FIG. 3.
 The broken lines depict portions of the combined wireless
 earphones and case that form no part of the claimed design.
 The dot-dashed broken lines in FIGS. 2, 3 and 8 show the
 boundary of the enlarged views of the combined wireless
 earphones and case and form no part of the claimed design.

1 Claim, 25 Drawing Sheets
